MORTIMER E. MOORE, OF HIGHLANDS, NEW JERSEY

MATCH CONTAINER

Application filed January 12, 1931. Serial No. 508,257.

The present invention relates to smokers' appliances and the primary object of the invention is to provide a match container for use in pocket size tins of smoking tobacco whereby both the tobacco and matches may be carried in a single receptacle.

A further object is to provide a partitioning device for tobacco tins whereby a match compartment is formed along one side edge 10 of the tin or container and sealed from the tobacco compartment when the cover is closed.

A further object is to provide a match container of novel construction whereby the 15 matches are so retained as to be easily dispensed singly and without crowding.

A further object is to provide a device of this character which is of such simple construction as to permit economical manufacture thereof and thus readily associated with 20 pocket size tins of tobacco without objectionably increasing the cost thereof.

A further object is to provide a match container which may be readily applied to tobacco tins as now in general use.

Other objects and advantages of the present invention will be apparent from the following detailed description taken in connection with the accompanying drawings forming 30 a part of this specification and in which drawings:

Figure 1 is a vertical section thru a tobacco tin or receptacle provided with the match container.

Figures 2 and 3 are sections on the respective lines in Figure 1.

Figure 4 is a fragmentary sectional view showing the cover in a closed position.

Figure 5 is a perspective view of the device removed from the receptacle.

Figure 6 is a perspective view showing the manner of removing a match without permitting loss of tobacco.

In the drawings and wherein similar reference characters designate corresponding parts thruout the several views, the letter A designates a receptacle and B the match container for dividing the receptacle into tobacco and match compartments.

The receptacle A is in the form of the or-

dinary pocket size tins of smoking tobacco and comprises a body portion embodying the flat side walls 5 joined by the rounded ends 6. Closing the lower end of the body portion is a bottom wall 7, while the upper end of the body portion is closed by a hinged cover 8, 55 hinged to one of the side walls 5. The cover 8 is of usual construction and has the down-turned flange about the flat body portion of the cover.

Referring now to the container B, the same is intended to be arranged in the receptacle A to provide a tobacco compartment 9 and a match compartment 10. The container B is preferably made from sheet metal similar to that of which the receptacle A is made and comprises an elongated channel shaped body portion 12 providing a web portion 13 and side flanges 14. The web portion 13 is of a width equal to the spacing between the receptacle walls 5 and of a length slightly less than the height of the receptacle. The side flanges 14 are transversely arcuated to conform to the internal curvature of the rounded ends 6 of the receptacle A. When the container B is 60 inserted into the receptacle A, with the flanges 14 extending into one of the rounded ends 6, the web portion 13 forms a partition 65 wall defining the minor semi-circular shaped compartment 10 for receiving the matches 15 and the major compartment 9 for receiving the tobacco package 16.

Projecting from the lower end of the web portion 13 is a bendable tab 17 preferably having a pointed lower end as shown in Figure 5, and which tab is passed thru a slot 18 in the bottom wall 7 of the receptacle and bent flat against the outer surface of the wall to secure the container in position.

Bent inwardly at a right angle from the upper end of the web portion 13 is a top flange 20 which is spaced below the top of the receptacle when the container is in position. Bent upwardly and outwardly at an angle from the inner edge of the top flange 20 is a sealing flange 21 which projects slightly past the top of the receptacle when the cover 8 is in an open position. When the cover 8 is closed, the flat plate portion of the cover engages the free edge of the sealing 95 flange 21.

flange 21 and seals the match compartment from the tobacco compartment so that moisture from the tobacco will not enter the match compartment nor any odor of the matches enter the tobacco compartment.

5   Provided at the upper end of each flange 14 is an arcuate shaped wing 22 and these wings are preferably slightly longer than the flanges 14 and co-act with the top flange 20 to form retaining means for a substantially semi-circular shaped retainer plate 24 serving as a closure for the upper end of the match compartment 10. This retainer or closure plate 24 projects beyond the inner end 10 of the top flange 20 and is upwardly bent at a slight angle as shown. Provided at the central portion of the rounded edge of the closure plate 24 is a notch 25 forming a delivery opening permitting escape of one match at a time from the match compartment.

15   Arranged midway the ends of the container body portion 12 is a semi-circular shaped separator plate 26 which divides the match compartment into upper and lower match receiving sections having communication with each other thru a notch 27 provided at the central portion of the rounded edge of the separator plate. This notch 27 provides an 20 opening thru which one match may pass at a time. The plate 26 is held in position transversely of the body portion 12 by means of integrally formed ears 28 extended thru slots formed in the flanges 14 and then bent 25 over against the flanges. The plates 24 and 26 both have their straight edges engaging the web 13 and their rounded edges engaging the inner surface of one rounded end of the receptacle.

30   When desiring to obtain a match from the match compartment 10, the receptacle may be held in an angular position as shown in Figure 6 with the match compartment lowermost and the user's forefinger closing the tobacco compartment to prevent loss of loose tobacco in the compartment. A slight shaking of the box will cause one match to slide thru the delivery opening formed by the notch 25.

35   When the receptacle is in a match delivering position as in Figure 6, the angularly bent portion of the closure plate 24 serves to direct the ends of the matches to the delivery opening, while the rounded end of the receptacle causes the matches to assume a parallel relation longitudinally of the match compartment. The sections of the match compartment are but slightly longer than the length of the matches to be used and the separator plate 26 prevents wedging and binding of 40 the matches during handling of the receptacle by retaining the matches in one section from partially interfitting with the matches in the other section. As the matches are withdrawn thru the delivery opening 25 from the upper section of the match com-

partment, the matches in the lower section of the compartment will work thru the opening 27 into the upper section of the compartment. When tobacco is being removed from the receptacle, the match compartment is disposed uppermost and the matches are prevented from escaping by the plate 24.

45   Thus it will be seen that an improved combination receptacle for tobacco and matches has been provided wherein the matches may be loosely disposed in the match compartment and dispensed singly therefrom without likelihood of the matches becoming wedged in the compartment. It will also be apparent that a novel arrangement has been provided 50 whereby the container may be associated with the conventional types of tobacco tins or receptacles, and the match compartment sealed from the tobacco compartment when the cover is in a closed position.

55   Changes in detail may be made to the form of invention herein shown and described without departing from the spirit of the invention or the scope of the following claims.

I claim:

60   1. A device of the class described comprising a receptacle, a removable cover therefor, and a match container comprising a channel shaped body portion fitting in the receptacle and extending short of the cover, said portion 65 providing match and tobacco compartments, a retaining plate closing the upper end of the match compartment and having a delivery opening, a spring metal sealing flange extending from the retaining plate upwardly into spring contact with the cover, and means securing the container in position in the receptacle.

65   2. A device of the class described comprising a receptacle, and a match container comprising a channel shaped body portion fitting in the receptacle and providing match and tobacco compartments, a retaining plate closing the upper end of the match compartment and having a delivery opening, a separator plate dividing the match compartment into separate match receiving sections having communication thru the separator plate, and securing means for the container.

70   3. In a tobacco tin, a receptacle including side walls, rounded ends and a bottom wall, and a match container including a channel shaped body portion arranged in the receptacle adjacent one rounded end and providing match and tobacco compartments, a retaining plate closing the upper end of the match compartment and having a match escape opening, a notched separator plate midway the ends of the channel shaped body portion and providing separate match retaining portions, said plates conforming to the shape of the rounded end of the receptacle, and a tongue at the lower end of the body portion for connection to the bottom wall of the receptacle.

4. In a tobacco tin, a receptacle including side walls, rounded ends and a bottom wall, a hinged cover closing the upper end of the receptacle, and a match container in the receptacle adjacent one rounded end including a channel shaped body portion providing a web section dividing the receptacle into match and tobacco compartments extended throughout the height of the receptacle, a notched retaining plate at the upper end of the match compartment, a notched separator plate intermediate the ends of the match compartment, means for securing the lower end of the body portion to the bottom wall of the receptacle, and a sealing flange at the upper end of the web section above the retaining plate and engageable by said cover when closed to seal the match compartment from the tobacco compartment.
5. In a match container for the purpose described, a channel shaped body portion providing a web and side flanges, a top flange bent inwardly from the upper end of the web, a retaining plate held beneath the top flange and having a notch in its outer edge, a separator plate secured to the side flanges midway the ends of the body portion, and having a notch in its outer edge, and an attaching tongue extending from the lower end of the web.
6. In a match container for the purpose described, a channel shaped body portion providing a web and side flanges, a top flange bent inwardly from the upper end of the web, a semi-circular shaped retaining plate held beneath the top flange and having a notch provided at the center of its rounded edge, a semi-circular shaped separator plate mounted midway the ends of the body portion and having a notch in the center of its rounded edge, a sealing flange extending upwardly from the top flange, and an attaching tongue at the lower end of the body portion.
7. In a match container for the purpose described, a channel shaped body portion providing a web and side flanges, a top flange bent inwardly from the upper end of the web, a semi-circular shaped retaining plate held beneath the top flange and having a notch provided at the center of its rounded edge, a semi-circular shaped separator plate mounted midway the ends of the body portion and having a notch in the center of its rounded edge, a sealing flange bent upwardly at an angle from the inner edge of the top flange, and a bendable securing tongue extending from the lower end of the web.
8. In a match container for the purpose described, a channel shaped body providing a web portion and side flanges, said flanges being transversely curved inwardly, a top flange bent inwardly from the upper end of the web portion, a sealing flange projecting upwardly from the top flange, a semi-circular shaped retaining flange arranged beneath the top flange and having a notch provided at the center of its rounded edge, said plate beyond the top flange being bent upwardly, arcuate securing wings engaging beneath the plate, a semi-circular shaped separator plate arranged midway the ends of the body and having securing ears for connection with said side flanges, said separator plate having a notch provided at the center of its rounded edge, and a bendable tongue formed at the lower end of the web portion.
- MORTIMER E. MOORE.
9. In a match container for the purpose described, a channel shaped body portion providing a web and side flanges, a top flange bent inwardly from the upper end of the web, a retaining plate held beneath the top flange and having a notch in its outer edge, a separator plate secured to the side flanges midway the ends of the body portion, and having a notch in its outer edge, and an attaching tongue extending from the lower end of the web.
10. In a match container for the purpose described, a channel shaped body portion providing a web and side flanges, a top flange bent inwardly from the upper end of the web, a semi-circular shaped retaining plate held beneath the top flange and having a notch provided at the center of its rounded edge, a semi-circular shaped separator plate mounted midway the ends of the body portion and having a notch in the center of its rounded edge, a sealing flange extending upwardly from the top flange, and an attaching tongue at the lower end of the body portion.
11. In a match container for the purpose described, a channel shaped body portion providing a web and side flanges, a top flange bent inwardly from the upper end of the web, a semi-circular shaped retaining plate held beneath the top flange and having a notch provided at the center of its rounded edge, a semi-circular shaped separator plate mounted midway the ends of the body portion and having a notch in the center of its rounded edge, a sealing flange bent upwardly at an angle from the inner edge of the top flange, and a bendable securing tongue extending from the lower end of the web.
12. In a match container for the purpose described, a channel shaped body providing a web portion and side flanges, said flanges being transversely curved inwardly, a top flange bent inwardly from the upper end of the web portion, a sealing flange projecting upwardly from the top flange, a semi-circular shaped retaining flange arranged beneath the top flange and having a notch provided at the center of its rounded edge, said plate beyond the top flange being bent upwardly, arcuate securing wings engaging beneath the plate, a semi-circular shaped separator plate arranged midway the ends of the body and having securing ears for connection with said side flanges, said separator plate having a notch provided at the center of its rounded edge, and a bendable tongue formed at the lower end of the web portion.
